HEATING, HUMIDIFYING, AND VENTILATING APPLIANCE

Filed May 1, 1926

UNITED STATES PATENT OFFICE

CHARLES A. MOORE, OF EDINA, MINNESOTA

HEATING, HUMIDIFYING, AND VENTILATING APPLIANCE

Application filed May 1, 1926. Serial No. 106,141.

My invention relates to improvements in heating, ventilating and humidifying appliances.

An object of the invention is to provide an efficient device of the present nature which is simple, durable and inexpensive, and which is readily adapted to be constructed in unitary form for convenience in shipment and installation.

With the foregoing and other objects in view, which will appear in the following description, the invention resides in the novel combination and arrangement of parts and in the details of construction hereinafter described and claimed.

In the drawing, Fig. 1 is a plan view of an appliance embodying my invention; Fig. 2 is a vertical sectional view taken on the line 2—2 of Fig. 1 and representing walls, floor and ceiling of a structure forming a chamber in which the appliance is installed; Fig. 3 is also a vertical sectional view, the same being taken as on the line 3—3 of Fig. 2, and Fig. 4 is a horizontal sectional view of the appliance taken on the line 4—4 of Fig. 3.

Referring to the drawing, it will be observed that the represented walls 10, floor 11 and ceiling 12 comprise a structure forming a chamber A. The illustrated embodiment of my invention, shown as installed in the chamber A, includes an upright casing 13 of sheet metal provided with a slightly elevated floor 14 and a top 15, said casing being fitted at its lower margin with a reinforcing footing 16 of angle iron. An air ingress duct is provided, the same including a horizontal pipe 17 and an upright pipe 18, the former extending transversely through the casing 13 at one side of the middle thereof. The upright pipe 18 is joined at its lower end with pipe 17 within the casing 13 and extends upward through the top 15 of the casing to a point near the ceiling of chamber A. One end of the horizontal pipe 17 projecting from the casing 13, is extended to reach through

a wall 10 of the chamber A, a damper 19 being fitted in said extended end of said pipe and accessible from within the chamber. The other end of pipe 17 is fitted with a removable cap 20. Within said horizontal pipe 17 are a pair of spaced, segmental end plates 21, which together with this pipe form a water receptacle B directly beneath the lower end of the upright pipe 18. Supplying said receptacle B is a water pipe 22, the same being fitted with an ordinary cut-off valve 23 and also with a conventional float feed valve 24 actuated by a float lever 25 carrying a float 26 at the free end thereof. This valve 24 operated by the float 26 and lever 25 insures a constant given level of water within the receptacle B. Burners 27 disposed beneath the water receptacle B in the horizontal pipe 17 are fed from a gas pipe 28 and heat, not only the interior of casing 13, but pipes 17 and 18 and the water in receptacle B, as well. An air egress duct is also provided, the same including an upright pipe 29 and a horizontal pipe 30 branching off from said pipe 29 near the upper end thereof and extending through wall 10 of the chamber A. Upright pipe 29, standing in the casing 13 alongside said first upright pipe 18, is soldered or otherwise suitably secured at its lower end to the floor 14 and opens at said end into the space beneath said floor, said space having communication with the chamber A through a series of openings 31 formed in the casing 13 along the lower marginal portion thereof. The upper end of pipe 29, extending through the top 15 of the casing 13, is secured to the top 15 by solder or other means, like expedients being employed to secure pipes 17 and 18 to the casing 13 and top 15 respectively, whereby tight and firm joints between said pipes and casing members are provided.

Traversing the casing 13 between the upright pipes 18 and 29 is a baffle wall 32, the lower end thereof meeting the floor 14 of the casing 13 and the upper end stopping short of

the top 15. This baffle wall 32 forms, within the casing 13, a flue C about the pipes 17 and 18 and a down flue D about the pipe 29. Said baffle wall 32 is in contact throughout its length with the pipe 29 and not only serves to reinforce said pipe but is in turn reinforced thereby. This feature is advantageous in that said wall and pipe and their fastenings to the casing are protected during the handling and shipping of the appliance. This pipe 29 is formed with a series of openings 33 in the side thereof near its bottom to provide communication between the down flue D and said pipe. The casing 13 is also formed with an opening 34, near the bottom thereof, on the side of the baffle wall 32 opposite said pipe 29 to afford communication between the chamber A and the up flue C, whereby air may be admitted to said up flue to support combustion at the burners 27 and to be heated thereby. Near the burners 27 are guard plates 35 and 36, the former being mounted on the casing 13 to shield the same from flames of the burners 27 and the latter being mounted on the baffle wall 32 to shield said wall.

A damper 37, fitted within the upper end of upright pipe 29, above the junction of the horizontal pipe 30 therewith, is normally closed, but may be opened at times in the use of the appliance which will now be described.

To heat, ventilate and humidify, the cut-off valve 23 in the water pipe 22 is opened and so also is the damper 19 in pipe 17, the cap 20 being fixed in place on the end of said pipe 17 and the damper 37 in pipe 29 closed. Upon the lighting of the burners 27, air enters the opening 34 in the casing 13 from the chamber A, passing into the up flue C where it is heated by said burners. Thus heated, said air rises to the upper portion of the up flue C and is thence drawn down the down flue D, through the openings 33, into the pipe 29 by the up draft existing therein. This up draft in the pipe 29 is increased by reason of said pipe being heated at the exterior thereof by the down traveling hot air and gases in the down flue D. Fresh outer air is drawn into the horizontal pipe 17 where it picks up vapor from the heated water in the receptacle B. the draft urging said air into the horizontal pipe 17 being created by the heating of the upright pipe 18, said draft causing the incoming, moisture treated air to rise in pipe 18 and to be further heated therein. Entering the upper portion of the chamber A from pipe 18, the fresh heated and moistened air descends by gravity to the floor of the chamber A along the relatively cold walls of said chamber. Following the floor 11 of the chamber A, said now comparatively cool air enters the openings 31 in the casing 13 beneath the floor 14 thereof and is exhausted upwardly and out of the chamber A through the pipe 29 and pipe 30 together with the hot air and gases entering said pipe 29 from the down

flue D. Thus, it will be understood that fresh air heated and moistened is brought into the chamber A and after circulating therethrough is exhausted to the outside.

Excessive moisture in the air in chamber A may be avoided by opening the damper 37 more or less and thereby permitting the escape of the air of greatest percentage of humidity from the chamber A at the ceiling thereof. Heating and ventilating may be accomplished without humidifying the air by leaving the damper 19 in pipe 17 open, cap 20 applied to pipe 17 and cut-off valve 23 closed. Heating and internal circulation of air in the chamber A without ventilation may be had by closing damper 19 in pipe 17 and removing cap 20 from said pipe. No ingress of air being provided, the air within the chamber A circulates from the lower to the upper portion thereof through the pipes 17 and 18. Also, ventilation and internal circulation may be accomplished by opening the damper 19 in pipe 17, while cap 20 is removed from said pipe.

Changes in the specific form of my invention, as herein disclosed, may be made within the scope of what is claimed without departing from the spirit of my invention.

Having described my invention, what I claim as new and desire to protect by Letters Patent is:

1. The combination with a structure forming a chamber, of an appliance therein comprising a casing having a floor and a top, an ingress duct including a horizontal pipe extending through the casing and supported thereby, one end of said pipe communicating with the outer air through a wall of the chamber, a closure for the other end of said pipe, said ingress duct further including an upright pipe connected at its lower end with said horizontal pipe within the casing and extending through said top to a point near the ceiling of the chamber, an egress duct including an upright pipe supported by said floor and top, the lower end of said pipe opening through said floor and the upper end thereof extending through said top to a point near the ceiling of the chamber, said egress duct further including a horizontal pipe branching off from said second upright pipe near the upper end thereof and communicating with the outer air through a wall of the chamber, an upright baffle wall traversing the casing between said two upright pipes and extending from the floor of the casing to a point near the top thereof, said casing having an opening beneath said floor and also having an opening above the floor on the side of the baffle wall beneath said first horizontal pipe, said second upright pipe having an opening in the side thereof above said floor near the same, a receptacle for water within said first horizontal pipe, and a burner with

in the casing beneath said pipe for heating the water in said receptacle.

2. The combination with a structure forming a chamber, of an appliance therein comprising a casing having a floor and a top, an ingress duct for admitting air from the outside at the lower portion of the chamber and conveying it upward to the upper portion of the chamber, said ingress duct including a pipe enclosed, in part, within the casing and supported by said casing and the top thereof, an egress duct for exhausting air from the lower portion of the chamber to the outside at the upper portion of said chamber, said egress duct including a pipe enclosed, in part, within the casing and supported by the floor and top thereof, an upright baffle wall traversing the casing between said upright pipes and rising from said floor to a point near the top of the casing, said wall being braced by and serving to brace one of said pipes, said wall providing an up flue about the first pipe and a down flue about the second pipe, the second pipe having an opening in the side thereof affording communication between the same and said down flue near the floor of the casing, said casing having an opening near the bottom thereof affording communication between the lower portion of the chamber and the corresponding portion of said up flue, and a heating element within the casing in said up flue for heating said first pipe.

3. An appliance comprising a casing having a floor and a top, an ingress duct including a horizontal pipe extending into the casing above said floor, said ingress duct further including an upright pipe connected at its lower end with said horizontal pipe within the casing and extending through said top, an egress duct including an upright pipe supported by said floor and top, the lower end of said last mentioned pipe opening through said floor and the upper end thereof extending through said top, an upright baffle wall traversing the casing between said two upright pipes and extending from the floor of the casing to a point near the top thereof, said wall engaging said second upright pipe, said casing having an opening beneath said floor and also having an opening above the floor on the side of the baffle wall beneath said first horizontal pipe, said second upright pipe having an opening in the side thereof above and near said floor, and a burner within the casing beneath said first horizontal pipe.

4. The combination with a structure providing a chamber, of an appliance comprising an ingress duct for admitting outer air into the chamber and conducting it upwardly therein to the upper portion thereof, and an egress duct for conducting air upwardly from the lower portion of said chamber to the outside, each of said ducts including an

upright pipe, a casing enclosing corresponding portions of said pipes, a burner within the casing, an upright baffle plate extending across the interior of said casing between said pipes and, together with said casing, forming one flue, opening above the burners, and a second flue in reversed continuation of said first flue, said second flue communicating at its lower portion with said egress duct.

In testimony whereof, I have signed my name to this specification.

CHARLES A. MOORE.
